UNITED STATES PATENT OFFICE.

WILLIAM J. HOBERG, OF JERSEY CITY, NEW JERSEY.

ABRASIVE DEVICE.

Application filed August 11, 1922. Serial No. 581,189.

To all whom it may concern:

Be it known that I, WILLIAM J. HOBERG, a citizen of the United States, and resident of 68 Lembeck Ave., Jersey City, in the county 5 of Hudson and State of New Jersey, have invented certain new and useful Improvements in Abrasive Devices, of which the following is a specification.

This invention relates to fruit and vegetable manipulating machines in general, and particularly to the kind used for abrading the outer skin of fruits or vegetables.

The prime objects of my invention are to provide a simple, inexpensive and effective 15 device of this kind which will effect a thorough cleansing of the surface of an article to be abraded.

Another object of my invention is to provide means whereby an article is flexibly 20 held while being subjected to a series of abrasive operations.

Another object of my invention is to provide within such device, means whereby an article is first cleansed at its periphery, substantially parallel to its long center axis, and means whereby the surfaces substantially parallel to the short center axis of the 25 article are thoroughly cleansed.

Another object of my invention is to provide a self adjusting combination cleansing and ejecting element, by means of which the cleansed article is fed out of the machine.

Another object of my invention is to provide a driving mechanism, adapted to operate a plurality of abrasive elements in opposite directions to each other, and also operating the ejecting element in a direction perpendicular to the operation of the abrasive 30 elements.

The foregoing and further objects will be more fully apparent from the following description and the accompanying drawings, forming part of this specification, and in 35 which:

Figure 1 represents a cross sectional view taken on line 1—1 of Fig. 2.

Figure 2 is a top view partially in section taken on line 2—2 of Fig. 1.

Figure 3 is a sectional view taken on line 50 3—3 of Fig. 1.

Figure 4 is a detail view showing the combination abrasive and ejecting element.

Figure 5 is a detail view of an eccentrically 55 arranged abrasive element.

Figure 6 is a diagrammatical view show-

ing the arrangement of the stationary holding, rotary abrasive, and the ejecting elements.

Referring to the drawings, numeral 10 60 denotes the base plate of my device to which is mounted a removable housing 11 held by convenient means 12 in proper relation to the base plate 10.

The housing is preferably provided with 65 a hopper 13 for receiving the articles to be cleansed. The housing is provided at one side with bearings 14 in which is rotatably mounted a driving shaft 15 operated either by means of a motor or by hand.

Shaft 15 extends into the housing and at 70 its inner end there is attached thereto by means of a key, a friction wheel 16.

Slipped over the shaft and bearing against the inner surface of the housing is a step-down collar 17 adapted to receive one end of an expansion spring 18 which bears with its 75 other end against the wheel 16, keeping the latter in frictional engagement with the rotary abrasive elements, the function of which 80 will be explained later.

Extending upward from base plate 10, and securely held in tubular extensions 19 and prevented from rotation by means of set screws 20, is a plurality of pins 21. Upon 85 these pins are mounted lower rollers 22 and upper rollers 23 adapted to freely rotate thereon. The free ends of the pins are held together by means of a ring-shaped plate 24 provided with perforated lugs 25 which are 90 slipped over the threaded portion of pins 21 and held down by means of nuts 26.

Attached to plate 24 there is a stationary concentric holding member 27, which consists of a ring-shaped frame from which extend radially towards the center, a plurality of bristles 28, leaving free the central opening 29.

Below the stationary holding member 27 there is mounted within rollers 23 a rotary 100 abrasive element 30 composed of an inner annular frame 31, which is eccentrically lodged within the outer frame of the rotary element, as clearly seen in Fig. 5.

Extending from the periphery of the concentric frame 31, is a plurality of abrasive members or bristles 32 which are so arranged as to leave a free circular opening 33 and are disposed at a tangent to the periphery of that central opening.

This arrangement of the bristles is very important because of its function upon the

object to be cleansed. Assuming that there should be a potato subjected to the cleansing operation. It is well known that the potato possesses a plurality of irregular depressions at its surface. Assuming that the rotary abrasive element would be provided with truly radially disposed bristles, these bristles will not reach under the skin at all points of the surface of the potato, but will 10 so-to-speak wipe the skin; that means that they will bend and their ends will assume a position opposite to the direction of the rotation of the element.

My construction assures that the bristles, 15 being at a tangent to the periphery of the circular center opening, will so-to-speak dig under the skin of a potato at all points of contact with its surface. In this manner every one of the depressions is effectively 20 reached as the bristles are flexible and follow the contour of the potato surface.

By consulting the drawings it will be seen that below the rotary abrasive element 30 there is provided again a concentrically disposed 25 stationary holding element again consisting of an annular frame 34 and radially disposed bristles 35 leaving again a free circular center opening 36.

This holding element is attached to a 30 ring-shaped plate 37 from which extend perforated lugs 38, which latter are slipped over the recessed portion 39 of pins 21.

The off set indicated at 40 provides a bearing for rollers 23. Below the stationary 35 element 33 there is again a rotary abrasive element 41 constructed similarly to element 30 having, however, its bristles disposed in opposite direction to that of abrasive element 30.

40 It will be seen that both abrasive elements have beveled corners 42 which correspond with the beveled edges 43 of rollers 22 and 23, respectively, by means of which these rotary elements are guided in a horizontal 45 plane.

By rotating shaft 15 friction wheel 16 with its inner face 44 engages the outer circumference of both abrasive elements 30 and 41. Assuming that shaft 15 rotates in 50 anti-clockwise direction, upper abrasive member 30 will also move in anti-clockwise direction, while lower abrasive member 41 will move in clockwise direction.

Below the lower abrasive member 41 and 55 yieldingly mounted in any convenient manner is an abrasive delivery brush 45 as clearly seen in Fig. 4. On its shaft 46 there is provided a friction wheel 47 which is held in engagement with the outer surface of friction wheel 16 by means of a spring. Friction wheel 47, which is caused to rotate in clockwise direction, causes abrasive 60 or delivery element 45 to also rotate in clockwise direction. The latter serves not only 65 to thoroughly clean the lower end of the

article passed through the machine, but also to eject the latter from within the machine after it has been thoroughly cleansed.

The swivel and flexible arrangement of the friction roller 47 and of the delivery element 45 has for its purpose to permit the ejection of articles which are so large that they would not normally pass by the ejecting element.

For the purpose of cleaning my device 75 and to permit the removal of the housing 11 from base 10, it is necessary to disengage friction wheel 16 from the rotary abrasive elements 30 and 41. This is accomplished by moving the shaft 15 in outward direction. 80 In order to enable shaft 15 to be held in its outward position, I have provided in the shaft a hole 48 which is normally disposed within bearing 14 and through which a pin may be inserted when the shaft is pulled 85 out. The pin prevents spring 18 from propelling shaft 15 in inward direction.

It is obvious that the specific construction shown in my drawings illustrates by no means a mechanically perfect device, and 90 I therefore reserve for myself the right to make such changes and improvements as will become necessary in constructing a commercially perfect machine.

Having thus described my invention, I 95 claim:

1. A machine, comprising a plurality of abrasive elements, including stationary and rotary elements, the latter disposed eccentrically relative to the former. 100

2. A machine, comprising a plurality of abrasive elements, including stationary holding and rotary working elements, the latter adapted to engage an object eccentrically while being held concentrically by the stationary elements. 105

3. A machine, comprising a plurality of abrasive elements, including stationary elements, rotary elements alternating with said stationary elements and a rotary delivery 110 element.

4. A machine, comprising a plurality of abrasive elements, including concentric stationary and eccentric rotary elements alternating with the former, and a delivery element. 115

5. A machine, comprising a plurality of abrasive elements, including stationary holding, rotary working and rotary delivery elements, and means for operating said rotary working elements in opposite directions to each other and said rotary delivery element in perpendicular direction to that of the said working elements. 120

6. A machine, comprising a plurality of abrasive elements, including stationary holding concentric elements, rotary working eccentric elements, and a rotary delivery element disposed perpendicular to said aforementioned elements, and means for simul- 125 130

taneously operating said working elements in opposite direction to each other and said delivery element in perpendicular direction to that of said working elements.

5. In a machine of the class described, a plurality of abrasive elements including stationary holding, rotary working and rotary delivery elements, driving means for said rotary elements, and means for permitting 10 said delivery element to automatically adjust itself when thrown out of alignment.

8. In a machine of the class described, a rotary abrasive element having a plurality of abrasive members, extending from its 15 periphery toward a free central circle but disposed at a tangent to the periphery of said central circle.

9. In a machine of the class described, a rotary abrasive element having a plurality

of abrasive members of equal length reaching from its periphery toward its center, leaving a free circular central opening, and disposed at a tangent to the periphery of 20 said circular opening.

10. A machine of the class described, comprising a pair of stationary abrasive elements, a pair of eccentric rotary abrasive elements alternately arranged with said stationary elements and adapted to rotate in opposite direction to each other, a delivery 25 element adapted to rotate in perpendicular direction to that of the rotary abrasive elements, and a friction drive operating said 30 rotary and delivery elements.

Signed at New York, in the county of 35 New York, and State of New York this 31 day of July A. D. 1922.

WILLIAM J. HOBERG.
